UNITED STATES PATENT OFFICE

HOWARD L. FISCHER, OF ST. PAUL, MINNESOTA, ASSIGNOR TO BROWN & BIGELOW, OF ST. PAUL, MINNESOTA, A CORPORATION OF MINNESOTA

PENCIL

Application filed April 7, 1924. Serial No. 704,783.

My invention relates to pencils and is particularly designed to provide a pencil wherein the mechanism will operate to propel and to also repel a marking lead. In one form of the invention the mechanism propels the lead and in the other the mechanism will propel and repel the lead by reason of the holding means provided for the marking lead.

The invention includes a simple and effective manner of forming the mechanism and part for holding the threaded portion or tube rigidly within the pencil barrel by having the rear portion of the same engage the barrel by friction in a similar manner as is shown and described in my Patent #1,370,420, of March 1st, 1921. This form of holding the threaded member within the pencil casing provides a simple, inexpensive construction and permits the holding of the threaded member without soldering the same to the pencil barrel and yet holds the threaded member against rotation in the barrel. In this construction the threaded member can be removed by exerting sufficient force against the threaded member to withdraw it from the pencil barrel or shell.

The forward end of the threaded member extends to the conical tip of the pencil and is supported or centered by the tip which forms the apex of the conical or writing end of the pencil. I provide a simple tip with a tapered shank which centers the forward end of the threaded member within the pencil casing and also holds the tip firmly in place in a novel and effective manner. The tip may be secured to the threaded member by a threaded connection or by friction to firmly hold the same in place.

This invention further includes a lead driving member which coacts with the threaded tubular member held rigidly within the pencil barrel in a manner to engage the threads of the threaded member so that the lead driving member will be held in threaded relation with the threads of the threaded member until the lead driving member reaches its extreme forward position. At this point the lead driving member is released and allowed to recede from the threads of the threaded member to permit the withdrawal of the lead driving member together with the propelling

means or operating member in which the lead driving member or nut with the lead engaging rod are adapted to slide.

My invention includes an operating member formed with a longitudinal slot through which the lead driving member or nut projects in a manner to engage the threaded member held rigidly in the pencil barrel. The longitudinal slotted member or propelling means is also provided with a track formed therein which forms a tracker for the outside of the nut of the lead driving member. The tracking means in the operating member is extended longitudinally and formed integral with the operating member, being elevated sufficiently to hold the nut of the lead driving member in frictional contact or threaded relation with the threads of the threaded member held rigidly in the pencil, until the nut reaches its forward extremity in the slot of the propelling member. At this point the propelling member is formed with a recess into which the nut recedes and permits the same to yield so as to change the threaded relation independent of the normal threaded movement, thus permitting the operating member to be withdrawn with the lead driving member without unscrewing the same in a similar manner as provided in my patent hereinbefore mentioned. The tracker portion formed in the operating or propelling member of my pencil may be cut in a manner to form a spring track on which the nut of the lead driving member is adapted to ride or bear against to hold the same under spring tension in contact with the threads of the threaded member fixed in the pencil.

It is also a feature of the invention to form the propelling or operating member which carries the lead driving means from sheet material, the same being formed in a manner to provide a lead magazine in the rear end of the same and an eraser socket at the back of the lead compartment. The cap for covering the eraser is held over the rear end of the operating member by friction and in a manner to compress the same on the rubber held therein. This provides an inexpensive construction for the lead propelling or operating member.

Other features and advantages of my pencil will be more fully pointed out in my specification and claims.

In the drawings forming a part of this specification:

Figure 1 is a sectional, side elevation of my pencil.

Figure 2 illustrates the propelling or operating member withdrawn from the pencil.

Figure 3 is an enlarged sectional detail of a portion of the writing end of my pencil.

Figure 4 is a section on the line 4—4 of Figure 2.

Figure 5 is a section on the line 5—5 of Figure 2.

Figure 6 is a central cross section similar to Figure 1 with a slightly different formation of my pencil.

Figure 7 is a detail of a portion of the pencil construction illustrated in Figure 6, a part of which is broken away and illustrated in cross section.

Figure 8 is a section on the line 8—8 in Figure 7.

In my pencil A the barrel 10 is formed of ordinary tubing and is swaged at 11 to form the barrel with a conical end, into which is fitted the writing tip 12.

The tip of the pencil A is formed of any suitable material and is provided with a constricted opening 13 to provide a support for the marking lead 14 which is adapted to be projected through the writing tip 12. The inner end of the writing tip 12 is formed with a tapered shank 15 which enlarges in toward the shoulder 16 formed adjacent the inner portion of the shank. The shoulder 16 is adapted to engage against the edge 17 of the swaged portion 11 of the barrel 10 when the tip is attached to the pencil. The tapered shank 15 properly centers the tip to the writing end or portion 11 of the pencil A.

The pencil A is provided with a threaded tubular member 18 which is formed with an unthreaded portion 19 and an expanded portion 20 which is adapted to rigidly and frictionally engage within the pencil barrel 10 at the rear end to hold the threaded member 18 firmly in the pencil barrel.

The forward end of the threaded member 18 is swaged or otherwise formed to provide a tubular portion 21 which is threaded on its outer end and adapted to engage with the shank 15 so that the shank forms a centering support for the tubular portion 21 and also assists in holding the threaded member 18 within the pencil barrel 10. The threads 22 of the threaded member 18 are formed in a suitable manner in the tubular member by rolling or otherwise, to provide a uniform thread fixed within the pencil barrel 10, ahead of the unthreaded portions 19 and 20 in a similar manner as illustrated in my patent hereinbefore mentioned.

The pencil A is provided with a propelling

member B, which may be formed of sheet material or tubing, is of a tubular construction so as to provide a magazine chamber 23 at the rear end thereof and an eraser socket 24 which is adapted to support the eraser 25 adjacent the rear of the magazine 23. An annular bead or shoulder 26 is provided against which the eraser covering cap engages to limit the inward movement of the same. The eraser cap 27 conceals the eraser and frictionally engages the outer surface of the socket 24 in a manner to compress the same onto the eraser and firmly hold the cap to the propelling member B so that when the cap 27 is engaged it is adapted to support or rotate the propelling member B within the threaded or tubular member 18 which is fixed in the pencil barrel.

The forward end of the propelling member B is formed with a longitudinal extending tracker 28 through which the lug 29 is adapted to extend so as to engage with the threads 22 of the member 18 the lug 29 is adapted to support the lead engaging rod 30 which, together with the lug 29, forms the lead driving member or plunger.

A tracker portion 31 is formed beneath the slot 28 and extending longitudinally therewith in a manner so that the undersurface 32 of the lug 29 will ride upon the same and hold the nut in engagement with the threads 22 of the member 18. The tracker portion extends the greater portion of the slot 28 and is formed by pressing the undersurface of the operating member B inward to provide a projecting track on which the nut is adapted to ride in the operating member B. At the forward end of the track 31 the recess 33 is formed by the natural formation of the tubular operating member B.

When the operating member B is within the pencil A, as illustrated in Figure 1, and the cap for head 27 is engaged in a manner to rotate the same, the nut 29 is rotated and is held by the tracker portion 31 and the frictional engagement with the threads 22 and when the lug 29 reaches the forward end of the slot 28 it will slide off of the tracker portion 21 permitting it to recede to the recess 33. At this point the lug 29 will disengage the threads 22 and the propelling member B can be withdrawn without rotating or unscrewing the same, thus providing a means cooperating with the carrier or lead pusher to permit yielding of the pusher to change the normal threaded movement.

In the construction of the pencil illustrated in Figure 6, the barrel 10 is the same as illustrated in Figure 1 and the tip 12 is similar in every manner excepting that instead of being secured to the portion 21 of the tubular threaded member 18 the tip is held by frictional engagement. In this construction the tapered shank 15 performs the same function, to center the forward end of the portion 21

and also firmly hold the tip into engagement with the edge 17 of the pencil barrel 10. The portion 21 in this illustration is a separate tubular piece which is adapted to engage within the swaging portion 34 formed on the end of the tubular threaded member 18 to simplify the manufacture. It is obvious that the member 18 can be formed from a single piece of material including the portion 21, however, if the portion 21 is formed from a separate piece of tubing it may provide a cheaper construction, which is just as effective, as where the part 18 is formed from a single part.

In the propelling member B illustrated in Figures 6 and 7 the tracker portion 31 operates in a similar manner as in Figure 1 excepting that the material of the propelling member B is cut in a manner so as to provide or cause the tracker 31 to provide a resilient means upon which the nut 29 is adapted to ride. In this construction the tracker 31 will curve upwardly when the lug 29 is out of engagement with the same and in the recess 33 as illustrated in Figure 7. The resilient tracker is illustrated in these views of my invention, and is adapted to hold the nut 29 into engagement with the threads 22 under spring tension and to compensate for the wear in the operating parts of the pencil and to provide resilient means for forming a frictional contact between the propelling member B, nut 29 and the threaded member 18. In this manner frictional contact is provided between these members so as to hold the same under uniform tension in operating and to prevent the free withdrawal of the propelling or operating member B while the lug 29 is in engagement with the threads 22. The shoulder 35 on the forward end of the slot 28 holds the lug 29 within the same and the enlarged portion formed on the nut holds the same against removal through the slot 28.

In this construction the rod 30 is provided with a lead receiving socket 36 which is adapted to hold the butt end of the marking lead 14 in a manner so that the same can be propelled and repelled in the pencil A. When the lead 14 is propelled and repelled as in the construction in Figures 6 and 7 the tip 12 is formed with the opening 13 of a size so as to slidably engage the marking lead by allowing it to slide through freely without binding so that the same can be propelled and repelled readily when the operating member B is rotated by engaging the head 27.

The tip 12 in the construction illustrated in Figures 1 and 3 is preferably slit longitudinally from the apex, in an ordinary well known manner, so as to form spring gripping jaws which engage the marking lead under fractional tension to hold the same within the pencil.

In the propelling member B, illustrated in Figures 6 and 7, I provide a spring locking

sleeve 37 which is freely rotatable between the shoulders 38 and 39 in a manner to be held against longitudinal movement and adapted to engage within the expanded portion 20 of the member 18 and to be held therein firmly against rotation to form a locking means to prevent the free movement of the operating or propelling member B when the pencil is in operation. This locking member 37 can also be readily applied to the construction illustrated in Figures 1 and 2 without departing from the spirit of my invention.

In Figure 8 I have illustrated a cross section of the member B which illustrates the spring tracker member 31 cut longitudinally of the member B in a manner so as to provide a sufficient resilient means to cause the nut 29 to engage the threads 22 under spring tension when the same is riding upon the tracker 31.

In accordance with the patent statutes I have described the principles of my invention together with the pencil which I now consider to represent the best embodiment thereof, but I desire to have it understood that the construction shown is only illustrative and that the invention can be carried out by other means and applied to other uses than those above set forth within the scope of the following claims:

I claim:

1. A pencil including a barrel, an internally threaded member in said barrel having an unthreaded portion adapted to fractionally engage in said barrel to rigidly hold said threaded member therein and a tubular member having a longitudinal slot on one side, a lead pusher carried by said tubular member and a resilient tracker formed in said tubular member adapted to hold the lead pusher in engagement with the threads of said threaded member.

2. A pencil, including a plunger to advance a lead, a threaded member held within said pencil, a propelling member including a lug connected to said plunger and adapted to be slidably supported within said propelling member and resilient means formed integral with said propelling member to hold said lug into engagement with the threads of said threaded member fixed in said pencil.

3. In a mechanical pencil having a barrel, a plunger to operate the lead, a threaded member engaging said plunger, an operating member for said plunger and a tracker means adapted to guide said plunger into or out of threaded engagement with said threaded member, said tracker means being adapted to yieldingly press against said plunger in a manner to take up inequalities and wear in the operating of said plunger.

4. A tracker in combination with a lead operating plunger and propelling means of a pencil including a track upon which said plunger is adapted to ride, a recess formed

in said track to permit the plunger to recede in order to change the operating position of the same, said tracker being formed integral with said propelling means and being resilient to compensate for inequalities and wear between the operating parts of the propelling means.

5. A propelling means for a mechanical pencil including a threaded member, a head for engaging the threaded member, an operating member adapted to carry said head longitudinally slideable therein, a resilient tracker formed in said operating member in a manner to hold said head into threaded relation with the threaded member of said propelling means.

10. 6. A propelling means for a mechanical pencil including a fixed threaded member, an operating member adapted to extend within said threaded member, a head carried by said operating member slideable longitudinally thereof and adapted to project from a slot in the same and a resilient tracker for supporting said head formed in said operating member in a manner to cause said head to be held in threaded relation with the threaded member under spring tension and to move out of threaded relation at the forward position.

15. 7. A mechanical pencil including a barrel, a threaded member, an unthreaded portion formed on either end of said threaded member, one end of said unthreaded portion being adapted to frictionally engage said barrel and a writing tip conically formed on either end to support the other end of said threaded member centrally within the barrel and facilitate drawing the same tight in said barrel.

20. 8. A mechanical pencil including a barrel, a threaded member, an unthreaded portion thereon adapted to fix said threaded member within said barrel, a tubular propelling member adapted to support a lead plunger longitudinally slideable in one end and formed with a magazine on the other end and a track for said plunger formed in said propelling member having a recess to permit changing the threaded relation of the plunger independent of the normal threading movement.

25. 9. A mechanical pencil comprising a casing, a lead feeding plunger, means for imparting movement to said plunger, and a spring guide member normally maintaining the plunger in engagement with said movement imparting means, throughout the major portion of its travel, and means in said guide member to release the plunger from said engagement at the limit of its lead feeding movement.

30. 10. A mechanical pencil comprising a casing, a lead feeding unit movable within the casing, means for causing the unit to travel within the casing, and a spring guide member normally maintaining said unit in en-

gagement with its travel causing means, throughout the major portion of its travel, said guide member having a depressed portion to release the unit from said travel causing means at the limit of its lead feeding 70 travel.

11. In a mechanical pencil the combination of a casing having a threaded portion and a tip, a plunger carrying member, and spring means for normally maintaining engagement of said member with the threaded portion of the casing, whereby said member may be caused to travel under spring tension within the casing to advance a lead through said tip, and means for releasing said plunger from said threaded portion when said member reaches a predetermined position in its travel.

12. A mechanical pencil comprising a casing, lead feeding means including a plunger operatively associated with the casing for movement longitudinally therein, an internally threaded member carried by said casing and a spring guide normally maintaining the plunger in resilient engagement with the said threaded member throughout the major portion of its travel, said guide having means to release the plunger at the substantial limit of its lead feeding travel.

13. In a mechanical pencil having an internally threaded member fixed in the barrel thereof, a propelling member rotatably held in said threaded member, a lead pusher including a lug adapted to engage said threaded member, and a tracker for said lug formed in said propelling member in a manner to hold said lug in normal threaded relation for the greater part of its travel, said tracker being shorter at the forward end than the thread of said threaded member to permit escape of the lug from the influence of the tracker and allow changing of the relative position of the lug and threaded member other than by the usual threading movement.

14. In a mechanical pencil having an internally threaded member fixed in the barrel thereof, a propelling member rotatably held in said threaded member, a lead pusher including a head adapted to engage said threaded member, and a resilient tracker for said head formed in said propelling member in a manner to hold said head under spring tension in normal threaded relation for the greater part of its travel, said tracker being shorter at the forward end than the thread of said threaded member to release said head from the influence of the tracker and threads and allow changing of the relative position of the head of the threaded member other than by the usual threading movement.

15. A propelling member for a mechanical pencil including a tubular member having 125

means for resiliently and slideably supporting a lead plunger within one end of the same, a magazine chamber formed on the other end of the same and an enlarged portion integral with and formed adjacent said magazine chamber adapted to receive an eraser.
